STOOL

Bertis F. Hamilton, Columbus, Ind.

Application April 28, 1954, Serial No. 30,234

Term of patent 14 years

(Cl. D15—8)

Fig. 1.

Fig. 2.

Fig. 3.

To all whom it may concern:

Be it known that I, Bertis F. Hamilton, a citizen of the United States, residing at Columbus, county of Bartholomew, State of Indiana, have invented a new, original and ornamental Design for a Stool, of which the following is a specification, reference being had to the accompanying drawing, forming a part hereof.

Fig. 1 is a front elevation of a stool, showing my new design;

Fig. 2 is a side elevation thereof; and

Fig. 3 is a plan view thereof.

I claim:

The ornamental design for a stool, as shown.
